UNITED STATES PATENT OFFICE.

DAVID M. COHN, OF EVANSVILLE, INDIANA, ASSIGNOR TO KRUCKEMEYER AND COHN,
A PARTNERSHIP COMPOSED OF BENJAMIN L. KRUCKEMEYER AND DAVID M. COHN,
OF EVANSVILLE, INDIANA.

BELT-BUCKLE.

1,250,970.

Specification of Letters Patent. Patented Dec. 25, 1917.

Original application filed May 29, 1916, Serial No. 100,545. Divided and this application filed May 1, 1917.
Serial No. 165,673.

To all whom it may concern:

Be it known that I, DAVID M. COHN, a citizen of the United States, residing at Evansville, county of Vanderburg, and State of Indiana, have invented certain new and useful Improvements in Belt-Buckles, of which the following is a specification.

This invention relates to belt buckles.

Wearers of men's belts encounter a tendency of the belt to rise and override the upper edge of the trousers, thus detracting from a neat appearance. Cloth loops have been provided on the front of the trousers waist band to hold the belt down at this point, but the dressy appearance of the buckle is thereby marred.

The object of my invention is the provision, on a belt buckle having a front plate which is designed to overlie the adjustable belt end, and a cam gripping bale or loop adapted to clamp the said belt end, of a finger or hook fixed to the rear of the front plate in such manner that the belt may pass thereunder and which will be adapted to engage the garment to obviate the above mentioned tendency and to improve the dressy appearance of the buckle and belt.

Certain modifications of the invention are hereinafter described and set forth in the accompanying drawings to illustrate that it may assume different forms, but as the invention is susceptible of other embodiments in other forms, the disclosure is to be considered as illustrative, rather than restrictive, of the scope of the invention.

In the accompanying drawings:

Figure 1 is a longitudinal sectional view showing one form of the invention and illustrating its use; and

Fig. 2 is a rear perspective view of a modification.

Referring first to Fig. 1, the buckle plate or body 1 has side flanges 2 in, which is journaled at 3 the loop 4 having cam or

wedge bar 5. One end 6 of the belt is made fast to the loop 4, and the other, or loose, end 7 is entered between the flanges 2 and clamped against the rear face of body 1 by the cam or wedge bar 5.

A cross bar 8 connects the flanges 2 and overlies the loose belt end 7. Carried by the bar 8 is a finger or hook 9 which is so disposed that it is adapted to engage the metal loop constituting a part of the front top fastener for the trousers. The hook or finger 9 prevents the buckle from rising and also keeps it, and the belt, from shifting around the body of the wearer.

In the form shown in Fig. 2, the bar 8 carries a fork or double hook 10 which is adapted to straddle the thread of the stem or shank of the front top buckle of the thread between the overlapping parts of the latter. This form is adapted for use where the trousers have a top button instead of a metal hook and loop fastening.

The present application is a division of my application for belt buckles, filed May 29, 1916, Serial No. 100,545.

Having thus described my invention, what I claim as new and desire to secure by Letters Patent is:

A belt buckle having a front plate provided with side flanges and designed to overlie the adjustable belt end, a loop hinged to said front plate and adapted for attachment to the fixed belt end and for clamping the adjustable belt end between itself and the front plate; and a cross bar connecting the side flanges and carried by the rear part of said front plate at the rear of the adjustable belt end, and adapted to overlie said belt end and a hook carried by said cross bar being adapted for retaining the buckle on a garment.

In testimony whereof, I hereunto affix my signature.

DAVID M. COHN.
